UNITED STATES PATENT OFFICE

110,018

DESIGN FOR A COMBINED TABLE AND RADIO SET

Daniel J. Crowley, Grosse Pointe, Mich.

Application March 14, 1938, Serial No. 75,813

Term of patent 14 years

To all whom it may concern:

Be it known that I, Daniel J. Crowley, a citizen of the United States of America, residing at Grosse Pointe, in the county of Wayne, and State of Michigan, have invented a certain new, original, and ornamental Design for a Combined Table and Radio Set, of which the following is a specification, reference being had therein to the accompanying drawing, forming a part thereof, wherein:—

The single figure illustrates a perspective view of a combined table and radio set embodying my design.

In my design of combined table and radio set, the rear elevation of the table top is identical to the front elevation, with the exception that the window exposing the dial of the radio receiving set is omitted and the adjacent sides of the table top are identical.

The dominant features of my design consist in that portion shown in solid lines.

I claim:

The ornamental design for a combined table and radio set substantially as shown and described.

DANIEL J. CROWLEY.
